UNITED STATES PATENT OFFICE.

COLUMBUS H. BISHOP, OF EL RENO, OKLAHOMA.

EGG TURNER.

Application filed November 29, 1921. Serial No. 518,631.

To all whom it may concern:

Be it known that I, COLUMBUS H. BISHOP, a citizen of the United States, residing at El Reno, in the county of Canadian and State of Oklahoma, have invented a new and useful Egg Turner, of which the following is a specification.

The device forming the subject matter of this application is an egg turner and the invention aims, primarily, to provide novel means whereby the egg trays of an incubator may be reversed, upon occasion, in order to secure a proper hatching of the eggs.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in section, a device constructed in accordance with the invention; Figure 2 is a horizontal section; Figures 3 and 4 are detail sectional views relating to the construction of the tray.

In carrying out the invention, there is provided a support 1 which may include a base 2 and a frame 3, the frame 3 embodying corner posts 4 connected at their upper ends, by top bars 5, and connected, below the top bars 5, by intermediate bars 6, the bars 5 and 6 connecting the posts 4 at the ends of the frame 3. The intermediate bars 6 are connected by longitudinal bearing bars 7. The frame, constructed as above described, may be closed in in any desired way, no covering for the frame being shown since this detail may be left to the manufacturer or the user.

On each bearing bar 7, a tray 8 is mounted rotatably, so that the tray can be reversed, thereby to dispose either side of the tray uppermost. The trays 8 may be constructed as desired. Preferably, each tray 8 is made up on frames 9 provided in their ends with cooperating notches 10, forming openings adapted to receive the bearing bars 7, so that the trays are pivotally mounted on the

bearing bars, for reversal, as aforesaid. The frames 9 of each tray may be connected along one of their longitudinal edges by hinges 11, and may be connected along the other of their longitudinal edges by latches 12, constructed as described. Each latch 12 may consist of a bolt 14 pivoted at 15 to a bracket 16 on one frame 9 and adapted to be received between ears 17 on a bracket 18 on the other frame 9, the bolt 14 carrying a wing nut 19 adapted to cooperate with the ears 17 of the bracket 16, as shown in Figure 4. Each frame is covered by a porous cushion 20, which may be a piece of burlap, the cushion being retained by an exterior layer of wire netting or other foraminous material, secured to the frame. Partitions 22 extend longitudinally of each frame 9, the bearing bar 7 being received therebetween. Cross partitions 23 extend from the partitions 22 to the sides of each frame 9 and define a plurality of compartments, each of which is divided up by partitions 24 into a plurality of egg cells 25.

In practical operation, the eggs which are to be hatched are placed in the cells 25 of one frame 9 of the tray 8, the other frame of the tray being closed down upon the first specified tray, and being held thereon by the latches 12, the bearing bars 7 being received in the openings defined by the notches 10. It will be obvious that any tray 8 may be reversed, to provide for a proper hatching of the eggs. By tightening up the latch bolts 14, the trays 8 may be held on the bearing bars 7 so that they will not tilt. This operation may be useful when the trays are not loaded symmetrically with eggs. It is not necessary that the trays in every instance comprise as many compartments and egg cells 25 as is shown in the drawings, this detail being left to the discretion of the user.

Having thus described the invention, what is claimed is:

1. In a device of the class described, a frame comprising side portions; a fixed bearing bar connecting the side portions of the frame; a tray comprising hingedly connected sections which are separable to receive the bearing therebetween; and a latch forming a releasable connection between the sections of the tray, the latch holding the sections of the tray on the bearing frictionally, whereby the tray will retain its position when loaded unsymmetrically, the tray being mov-

able on the bearing under the application of a sufficient force.

2. In a device of the class described, a frame including a fixed bearing; a tray including sections which are hingedly connected to receive the bearing therebetween; and means for clamping the sections of the tray on the bearing, with a frictional hold.

In testimony that I claim the foregoing as my own, I have hereto affixed my signature in the presence of two witnesses.

COLUMBUS H. BISHOP.

Witnesses:

JAMES I. PHELPS,
C. E. GRADY.
